CLAIM

The ornamental design for a asymmetrical dual cosmetic dispenser, as shown and described.

DESCRIPTION

FIG. 1 is a perspective view of an asymmetrical dual cosmetic dispenser, showing our new design;

FIG. 2 is a front elevational view thereof, the rear, left side and right side elevational views being identical thereto; and,
FIG. 3 is a top plan view thereof; and,
FIG. 4 is a bottom plan view thereof.

The broken circular outlines shown in FIGS. 1,3, and 4 are for illustrative purposes only and form no part of the claimed design.
